MELTING POT FOR TYPE-FORMING MACHINES

Herman T. Sundstrom, Houston, Tex., assignor of one-half to Walter B. Nail, Houston, Tex.

Application May 16, 1930. Serial No. 452,826

1 Claim. (Cl. 263—14)

My invention relates to the construction of the melting pot for the metal used in type-forming machines such as linotype machines and the like.

- 5 In the melting pot now generally used to supply the metal employed in casting the type, it is necessary to heat the crucible to about 550° F. so that the lead will be of the right fluidity to cast well. Also the outlet spout from the melting pot through which the molten lead passes to the mold must be of approximately the same temperature so that the lead will not be cooled before it enters the mold and so that the cast line of type may be easily detached from the discharge openings. To maintain the discharge spout of uniform high temperature it has been customary to provide a gas burner separate from the burner for the crucible and to then employ a third burner adjacent the outlet nozzle for the lead. This arrangement has many objections in that the burner at the outlet cannot be set to burn too strongly or the discharge nozzle plate is warped. If the flame is set low it frequently goes out.
- 23 It is an object of this invention to provide a structure for the melting pot and the burners thereof whereby the discharge port for the lead may be kept at the uniform temperature desired and the whole construction of the pot materially simplified.

I also wish to arrange to control the heating means for the outlet port so that it will be uniform and to disconnect the gas supply to the spout burner from the supply to the crucible burner and then prevent the varying of the heat supply to the outlet passage by the thermostat which controls the heat to the crucible.

The main idea of the improvement lies in the simplicity of the heating apparatus for the outlet pipe for the molten lead and the obtaining of a more uniform and continuous heat necessary in obtaining the best results in casting of the type slug.

45 In the drawing herewith Fig. 1 shows a central vertical section through the melting pot with the burner and its connection.

Fig. 2 is a perspective detail of a plate which I employ to close the draft opening ordinarily included in the usual melting pot.

Fig. 3 is a detail sectional view of one of the joints in the pipe shown in Fig. 1.

In carrying out my invention I have under contemplation the modification of the usual melting pot as now employed, and in Fig. 1 the

general construction of the pot is similar to that already old and now in common use.

Referring particularly to Fig. 1, the pot includes an outer housing 1, the rearward side of which is practically cylindrical and the forward side of which is curved forwardly at 2. The upper forward side has a discharge port 3 for the metal. Below this discharge port there is ordinarily an opening 5, which is a sort of draft opening, and in this opening there is usually a tubular burner fitting within an opening 4 in the side wall of the opening 5. The lower end of the housing is open at 6 to allow the insertion of the burner and its connections.

The housing thus provided has therein a crucible or pot 7, in which the lead is placed for melting. The forward side of the melting pot is inclined upwardly toward the outlet port for the lead. Approximately centrally of the melting pot is a cylinder 8, the lower end of which opens into an outlet spout 9, which is curved upwardly and forwardly to terminate at the discharge port 3. This construction is old and it is to be understood that the cylinder 8 is adapted to receive a piston, not shown, by means of which lead may be forced from the melting pot out the discharge port 3. This discharge port is of ordinary construction and has a series of small openings therein through which the lead is discharged to the mold which is forced against the discharge nozzle 3 when the cast is to be made.

The upper side of the housing has a cover 12 thereon in which is an opening 13, ordinarily closed by a lid and through which the lead may be fed to the crucible. The forward side of the cover is a chamber 14 separated from the main body of the crucible by a wall 15. This chamber 14 terminates in a chimney 16, opening upwardly to allow the escape of the fumes from the burner. There is a channel or passage indicated in dotted lines at 17 leading from the chamber 19 below the outlet passage upwardly to the chamber 14 so that the heat from this portion of the melting pot may find an outlet upwardly.

The main burner 20 is of ordinary construction and it is to be understood that it is positioned through the opening 6 directly beneath the bottom 21 of the pot. This burner is supplied with gas or similar fuel through a pipe 22 having air inlets thereto beneath the shield 23 on said pipe. Below the air inlets is a valve 24 through which the supply of gas through the pipe 25 may be regulated. The gas supply to the burner is admitted through a pipe 26 at the forward side and it will be seen that this pipe passes by way of a thermo-

stat 27 to the supply pipe 25. The thermostat is of the usual construction having a pair of terminals 28, which are fitted into the melting pot and the temperature of the pot may thus control 5 through the usual thermostat connections the amount of gas passing to the burner 20.

There are also two tubes 29 at the forward side of the burner 20. These two tubes conduct gas to the passage 19 below the discharge spout. The 10 gas leading to these two burner tubes comes by way of the pipe 30 with the air regulating device 31 thereon and the inlet pipe 32 connected with the supply pipe 26. In the old construction the gas supply to the burner tubes 29 came by way of 15 a connection 33 with the supply pipe 25. This supply would thus be controlled by the thermostat and each time lead was dropped into the crucible, thus tending to lower the temperature of the crucible, the thermostat would have the effect of 20 turning on more gas and delivering a hotter flame into the crucible until the new lead was melted. A full supply of gas would thus also be delivered to the burner tubes 29 with the result that whenever new lead was dumped into the melting pot 25 the outlet passage and the outlet port 3 would be overheated and damage to the apparatus would occasionally result and in any case the lead might be more fluid than was particularly desired.

In my present construction the pipe 30 is connected with the pipe 32, as shown in Fig. 3, but the connection by way of the pipe 33 is eliminated, and a solid rod or support takes the place of the tubular connection.

As a further change in connection with the device I eliminate the burner at the point 4 and close the opening between the walls 5 by means of a plate 34. This plate is shown particularly in Fig. 2. It is connected with the housing by means of screws 35 at the forward side of the opening and is extended rearwardly to entirely close this port or opening through which the draft was supplied 40 in the old construction. An inwardly turned

flange 36 at one end of the plate is necessary to close the opening through which the old burner would be projected.

It is to be understood that in the old construction there was a baffle across the passage 19 at the point indicated by the screw head 37, but in my present construction this baffle is eliminated and the heat from the burner tubes 29 may pass up through the chamber 19 and around beneath the lower side of the discharge passage and up 85 through the outlet 17 to the chamber 14 and then out through the chimney 16.

In the use of my device the operation of melting the lead and discharging the same to the mold is identical with the old construction. I am enabled, however, by passing the heat from the burner tubes 29 upwardly around the discharge port without the supply of cooling air through the port 5 and thus obtain an equal heating of this tube such as is particularly desired. A valve 90 40 in the supply tube 32 will enable the operator to regulate the heat in this passage to obtain the uniformity which was unobtainable in the old device and I also am enabled to eliminate an extra burner usually employed at the point 4 as has 95 been described. It has also been found an improvement to eliminate the thermostatic control of the burner 29 which in the old form caused unequal heat and occasional warping of the discharge device through which the lead is delivered 100 to the mold.

What I claim as new is:

A melting pot of the character stated including a housing, a crucible therein, an outlet spout thereon having a discharge nozzle, a metal heater below said crucible, thermostat means to control said heater, a spout heater spaced upwardly therefrom for said spout and nozzle and free of control from said thermostat, a chimney above said spout, and a laterally closed passage from 110 said heater about said spout to said chimney.
